CLAIM

The ornamental design for an electric mixer base unit, as shown and described.

DESCRIPTION

FIG. 1 is a front perspective view of an electric mixer base unit according to my new design;

FIG. 2 is a front plan view thereof;

FIG. 3 is a rear plan view thereof;

FIG. 4 is a left side plan view thereof;

FIG. 5 is a right side plan view thereof;

FIG. 6 is a top plan view thereof; and,

FIG. 7 is a bottom plan view thereof.

The broken lines illustrate environmental structure and form no part of the claimed design. Conventional shading is illustrated for purposes of highlighting the line drawings, but forms no part of the claimed design.

Any combination of the illustrated features, including claimed features and unclaimed features, may be claimed in this application or a continuing application claiming priority to this application by converting any portion of the broken lines to solid lines, any portion of the solid lines to broken lines, or both.

Our design is not limited to the exact details shown in the drawings, since equivalents and colorable imitations thereof will be evident to a person of ordinary skill in the art. Within the scope of the appended claim, in which we intend to cover only the ornamental and novel elements shown in the drawings, our invention may be practiced otherwise than as specifically shown and described herein.

1 Claim, 7 Drawing Sheets(56)
